UNITED STATES PATENT OFFICE.

GEORGE B. HANNAN, OF MARION, INDIANA.

TOOL.

1,281,950.

Specification of Letters Patent. Patented Oct. 15, 1918.

Application filed December 15, 1916. Serial No. 137,140.

To all whom it may concern:

Be it known that I, GEORGE B. HANNAN, a citizen of the United States, residing at Marion, in the county of Grant and State 5 of Indiana, have invented certain new and useful Improvements in Tools; and I do hereby declare the following to be a full, clear, and exact description of the invention, such as will enable others skilled in the art 10 to which it appertains to make and use the same.

This invention relates to tools and more particularly to a device especially designed for tinnery's use for forming sheet metal 15 pipes.

The invention has for its object to provide a pipe forming tool of novel and efficient construction embodying essentially two detachable parts, one of which is provided 20 with a shank adapted to be engaged between the jaws of a vise or in the aperture ordinarily provided in the heel or toe of an anvil, whereby the tool may be held stationary during use.

Another object is the provision of a pipe 25 forming tool embodying means whereby pipes of different diameters may be formed thereon.

With these and other objects in view, the 30 invention consists in the novel construction, arrangement and formation of parts as will be hereinafter specifically described, claimed and illustrated in the accompanying drawing, in which:

Figure 1 represents a perspective view of 35 the improved pipe forming tool.

Fig. 2 represents a fragmental perspective view of one of the parts of the tool removed from the other.

Fig. 3 represents a fragmental perspective 40 view of the other part of the tool removed, and

Fig. 4 represents a fragmental longitudinal 45 sectional view through the central portion of the tool, illustrating the parts assembled.

Referring to the drawing in detail, wherein similar reference numerals designate corresponding parts throughout the several 50 views, the numeral 5 indicates the shank of the tool which is preferably rectangular in cross section and provided with a tapered free end 5^a adapted to be received between the jaws of a vise or an aperture in an anvil, 55 whereby the tool may be held stationary during use. The upper extremity of the

shank 5 is provided with a head 6 in which is formed a recess 7 having a concavity 10 in the lower wall thereof. A pipe former or mandrel 8 is rigidly secured to or formed integral with the head 6 and projects laterally therefrom, and the end wall of the recess 7 is formed with a seat 11 adapted to receive the projection or stud 12 formed integral with and projecting longitudinally of 60 the other part of the tool which is designated generally by the numeral 13. The stud 12 is formed upon the head 14 of the removable part 13 of the tool and the lower surface of the head is formed with a convex 65 enlargement 15 adapted to engage within the concavity 10 in the head 6 of the other or stationary part. A pipe former or mandrel 16 is carried by the head 14 of the removable part and is of a different diameter 70 from the mandrel 8, whereby pipes of different diameters may be formed with the same tool.

The head 6 is formed with a longitudinal extension 17 in which is fitted a thumb screw 80 18 adapted to project into an internally screwthreaded aperture 19 formed in the lower surface of the head 14 of the relatively movable part, whereby the parts of the tool may be rigidly and effectively secured together. It will be understood that any desired number of the removable parts 13 of each tool may be provided, each mandrel 85 16 of the removable part being of a different size, whereby pipes of various diameters 90 may be formed with the same tool.

What I claim is:

1. In a tool, a shank, a head formed upon the upper end of said shank and having a concave recess formed in its upper surface 95 terminating short of one end of the head, a socket formed in the wall at the inner end of the recess, a second head, a convex enlargement formed upon the under surface of said second head for seating in said recess, 100 a lug formed upon the inner end of said second head for seating in said socket, and a mandrel formed upon said second head and extending outwardly from the ends thereof oppositely to the lug carrying end. 105

2. In a tool, a shank, a head formed upon the upper end of said shank and having a concave recess formed in its upper surface terminating short of one end of the head, a socket formed in the wall at the inner end of 110 the recess, a second head, a convex enlargement formed upon the under surface of the

second head for seating in said recess, a lug formed upon the inner end of said second head for seating in said socket, a mandrel formed upon said second head and extending outwardly from the end of the head oppositely to the lug carrying end, an ear formed upon said first named head for abutment against the under surface of said enlarge-

ment, and a set screw carried by said ear and extending into said enlargement.

10

In testimony whereof I affix my signature in presence of two witnesses.

GEORGE B. HANNAN.
